HENRY JEPSEN, OF COLLINSVILLE, CONNECTICUT

PACKAGING CEMENTING COMPOUNDS

Application filed December 6, 1928. Serial No. 324,220.

Manufacturing plants, garages and repair shops, ordinarily carry a stock of cementing material for mending leather and rubber belts and making other repairs requiring adhesive compounds which if exposed to the atmosphere become hard and take a long time to soften and render plastic. The quantity of adhesive used at any one time varies in amount depending on the damage 5 to be remedied, and the intervals of time between use vary considerably, sometimes there is a long period before the adhesive is required.

The object of this invention is to provide 10 a simple and cheap article of commerce which can be kept in stock by anyone desiring the occasional use of glutinous, gummy, or plastic cementing material, and which will permit the quick removal and use at any 15 time of as large or as small a quantity of the adhesive as is required for a particular repair and will keep for an indefinite time in prime condition for future use the adhesive not needed for that repair.

20 This object is attained by forming an article which comprises a cylindrical body of glutinous or gummy adhesive and an exterior casing of quite thin, soft and easily severed sheet metal, which casing is in the 25 form of a cylindrical tube that is threaded for practically its entire length, and that is provided with a threaded end closing cap which may be screwed upon the end of the casing wherever the casing is cut off to remove the quantity of adhesive that is required at the moment.

In the accompanying drawings Fig. 1 30 shows a side elevation of the article which embodies this invention. Fig. 2 shows a transverse section on the plane indicated by the dotted line 2—2 on Fig. 1. Fig. 3 shows a side view of the article with a section cut off, also the cap which has been unscrewed from the severed portion and is capable of 35 being screwed upon the end of the case of the remaining portion of the article; this view also showing in section a paper tube in which the article may be packed and shipped, and which can be used as a guide 40 for the tool with which the section contain-

ing the amount of adhesive that it is desired for immediate use is cut off, in order to ensure a square cut so that the cap may be screwed tightly upon the casing containing the portion of the adhesive which is not 55 needed at the time.

The adhesive 1 which forms the cylindrical body of the article illustrated and described herein as embodying the invention is particularly adapted for cementing leather 60 belting, although the adhesive body may be of a composition suitable for cementing other articles or material. For the purpose of cementing leather belting the adhesive is made of animal glue and water with a small 65 amount of carbolic acid added as a preservative. It is in a gummy, or glutinous, or viscous, or plastic condition and is made ready for use by adding water and heating 70 so that it will melt and dissolve.

This body of adhesive is encased in a cylindrical tube 2 preferably drawn of thin, soft, easily severed metal such as heavy lead foil or white metal which is suitable for the purpose. This tubular casing is spirally 75 corrugated by rolling threads in it, which threads stiffen the thin casing and at the same time permit the cap 3 which is made of heavier and stiffer sheet metal and has 80 threads of the same pitch as the casing, to be screwed upon the casing. Although the casing is formed of thin, pliable metal it, when filled with the adhesive, and owing to the threading corrugations, is quite stiff, but 85 being of soft metal it can be easily cut.

This article is preferably packed and 90 shipped in paper board tubes 4 which the article snugly fits. When it is desired to use a quantity of the adhesive the capped end of the article may be pushed from the paper tube and with the end of the tube as a guide a section which will contain just enough adhesive for the present use is cut off with a knife or saw. Thereafter the cap is screwed 95 upon the end of the casing containing the adhesive which is not used so that it will be practically hermetically sealed and will remain in condition for immediate future use. The casing of the section that has been cut off may be peeled from the adhesive body 100

or the cut section may be heated in warm water and the adhesive melted out of the thin casing. Should there not be enough adhesive for the particular job another section may be cut off.

- 5 With this article wherever the cut is made to obtain the supply of adhesive required, the cap may be immediately replaced on the remaining section as its threads will fit the
10 threads at all localities on the casing, which although made of very thin, soft metal, is sufficiently rigid when the adhesive is in the interior to permit easy and square cutting to remove the required quantity for use.
15 The casings are made of varying lengths depending upon the quantity of adhesive which they are intended to contain. This article which is cheap to produce, compact in size, easily shipped and stored, enables any-
20 one having occasional need for a readily soluble adhesive to keep the required quantity on hand for immediate use without waste, for the adhesive which is not used for the immediate work will keep for a long
25 time in good plastic condition.

The invention claimed is:

1. A package comprising an interior cylindrical body of glutinous adhesive and an exterior cylindrical casing of thin, soft, easily severed metal, which casing is spirally corrugated for substantially its entire length and is provided with a cap which is also spirally corrugated and is capable of being screwed upon the end of the casing wherever
35 the casing and the body are cut off.
2. A package comprising an interior cylindrical body of glutinous adhesive, a cylindrical casing of easily severed metal which casing is spirally corrugated for substantially
40 its entire length and is provided with a cap which is also spirally corrugated and is capable of being screwed upon the end of the casing wherever the casing and the body are cut off, and means to prevent distortion
45 of said casing, said means comprising a tube snugly fitting the said casing with the edge of said tube serving as a guide for severing the desired portion of the contents.
